UNITED STATES PATENT OFFICE.

RUSSELL J. TURNER, OF BANGOR, MICHIGAN

VALVE MECHANISM FOR INTERNAL-COMBUSTION ENGINES.

1,186,457.

Specification of Letters Patent. Patented June 6, 1916.

Application filed November 15, 1915. Serial No. 61,666.

To all whom it may concern:

Be it known that I, RUSSELL J. TURNER, a citizen of the United States, residing at Bangor, in the county of Van Buren and State of Michigan, have invented, new and useful Improvements in Valve Mechanism for Internal-Combustion Engines, of which the following is a specification.

This invention relates to a valve mechanism for internal combustion engines, and particularly to valve mechanism for internal combustion engines of the four-cycle type in which the combustible mixture is introduced into the engine cylinder and is compressed therein, and in which the burned gases, after combustion, are discharged from the cylinder prior to the introduction of a fresh charge.

The primary object of my invention is to provide an admission and exhaust valve mechanism composed of a valve sleeve and valve piston, arranged upon the exterior of the engine cylinder, and operating to control the admission of the combustible mixture and discharge of the burnt gases in a certain and efficient manner, and which shall be much simpler and less liable to wear and derangement than ordinary valve mechanism of the lift-valve type or sleeve-valve mechanisms of the kinds heretofore employed.

A further object of the invention is to provide a sleeve and piston valve mechanism in which the parts of the valve are so constructed as to permit of the free admission of the combustible mixture and free discharge of gases without restriction, liability of back pressure or other deleterious actions.

A still further object of the invention is to provide a valve mechanism in which the valve tends to operate as a pump to discharge the burnt gases on the exhaust stroke, and in which the exhaust is permitted without an unnecessary length of flow of the gases or undue tendency to heat the valve parts.

A still further object of the invention is to provide a valve mechanism which will keep comparatively cool at all times which is adapted to prevent leakage, which diminishes the deposit of carbon upon the working surfaces of the valve, and the tendency of such deposits to interfere with the free movement of the valve, in which the valve mechanism operates at a compara-

tively slow speed so as to reduce wear thereon, and in which the parts are simplified in construction to reduce the cost of manufacture and diminish liability of injury or derangement to the minimum.

With these and other objects in view, the invention consists of the features of construction, combination and arrangement of parts hereinafter fully described and claimed reference being had to the accompanying drawings in which:

Figure 1 is a side elevation, partially in vertical longitudinal section, through a four-cycle engine embodying my invention. Fig. 2 is a vertical transverse section on the line 2-2 of Fig. 1. Fig. 3 is a side elevation of the valve piston. Fig. 4 is a view looking toward another side thereof. Fig. 5 is a bottom plan view of the valve piston. Figs. 6, 7, and 8 are views corresponding to Figs. 3, 4, and 5 of the valve sleeve. Figs. 9 to 14, inclusive are diagrammatic views illustrating the action of the valve mechanism in the cycle of operation of the engine.

Referring now more particularly to the drawings, 1 designates an engine of the four-cylinder, four-cycle type, to which my invention is shown in the present instance applied, although it is to be understood that the number of cylinders may vary as occasion requires, the invention not being restricted in this particular.

In the illustrated example, 2 designates the crank case of the engine, 3 the cylinders, each provided with an admission and exhaust port 4, 5 the intake manifold, 6 the exhaust passage leading to the exhaust manifold 7, 8 the engine pistons, one of which is herein shown, and 9 the crank shaft of the engine, all of which may be of any ordinary or preferred construction.

10 denotes the water jacket of the engine, which may be arranged in the usual manner and also disposed about the valve casing, hereinafter described, to keep the valve mechanism cool.

The valve mechanism comprises a casing 11, one of which is formed upon a side of each cylinder 3, and each of these valve casings 11 is open at its lower end and communicates with the upper portion of the crank case, and connects at its upper end with the exhaust passage leading to the exhaust manifold 7. At its inner side the valve casing communicates with the admission and exhaust port 4 of the engine, and

at its outer side the valve casing is provided with an intake port 12 which is arranged somewhat below the level of the port 4 and communicates with the intake manifold 5.

Arranged to operate within each valve casing is a valve device comprising a valve piston 13 and a valve sleeve 14, which are fitted for reverse reciprocating motions within the cylinder and one arranged to operate within the other. As shown, the valve piston 13 comprises a cylindrical shell, open at the bottom and closed at the top, and provided with an inclined or diagonal passage 15 and segmental ports 16 and 17 communicating with the inner and outer ends of said passage, said ports 16 and 17 being adapted for co-operation with the respective ports 4 and 12. At its upper end the valve piston is provided at its outer side with an upwardly projecting shield or deflector 18, for a purpose hereinafter fully described.

The valve sleeve 14 comprises a shell which is open at top and bottom and closes the piston 13 which is fitted to slide therein. This shell is formed with grooves at top and bottom to receive packing rings 19 whereby leakage of the fuel mixture or gases between the surfaces of the sleeve and the valve casing will be prevented, and if desired the piston valve may be grooved and provided at its lower end with a packing ring 20 to prevent leakage between the surfaces of the valve sleeve and valve piston. In the valve sleeve, which is approximately of twice the length of the valve piston, are formed segmental ports 22 and 23, arranged at the inner and outer sides of said sleeve and adapted for co-operation with the ports 4 and 12 of the cylinder and valve casing and the ports 16 and 17 of the valve piston. The function of the deflector 18, which lies in the path of the exhaust gases discharging from the cylinder through the port 4 in the exhaust operation, is to serve as an abutment against which said gases may strike, and whereby such gases will be guided or deflected toward the exhaust outlet, thus preventing the same from coming in contact with the working surfaces of the sleeve thus preventing the deposit within any given time of an amount of carbon liable to interfere with the operation of the valve.

The valve piston and valve cage are respectively provided at their lower ends with cross pieces 24 by which they are coupled through the medium of connecting rods 25 and 26 to cranks or eccentrics 27 and 28 on a valve-operating shaft 29 arranged parallel with the crank shaft 9 and driven therefrom by suitable gearing shown in the present instance in the form of a sprocket pinion 29' on the crank shaft, a sprocket gear 30 on the valve operating shaft 29 and

a link belt or chain 31 connecting said sprocket elements, the ratio of the gearing being as 2 to 1, so that the shaft 29 will make one complete revolution of each two revolutions of the crank shaft 9. Each valve device as a whole, will, therefore, make one complete back-and-forth reciprocation during each two complete back-and-forth reciprocations of the engine piston, or on each cycle of operation of the engine. Hence each valve device will operate at a much lower rate of speed than the engine piston, with a reduction of wear and tear and increased period of usefulness.

The operation of the valve mechanism is as follows: Referring to Fig. 9, in which the ports of the respective parts are shown in register, at which time the cranks of both the engine shaft and valve operating shaft will be at the zero position, it will be evident that the fuel will pass from the intake manifold into the combustion chamber of the engine behind the engine piston upon the suction stroke of such piston. The ports will remain in register, owing to the limited motion of the valve members, during the entire suction stroke of the piston, as shown in Fig. 11, in which the piston crank of the engine shaft travels through an arc of 140° , while the cranks of the valve members travel through an arc of 70° , as indicated, or through an arc of one-half the number of degrees as that of the arc through which the piston crank travels. The piston will then begin its upward or compression stroke, compression beginning when the piston crank reaches a position of 210° and the valve cranks reach a position of 125° , during which ranges of travel of the piston and valve members from the position shown in Fig. 10, the valve sleeve and piston will have been moved downward so that the ports in the valve sleeve will be out of registry with the intake ports and partially out of registry with the ports in the valve piston, thus closing the intake ports and cutting off the admission of fuel to the engine.

From the 210° position the piston moves upward and compresses the mixture until the actuating crank of the piston has reached the 360° point or made one complete revolution, as shown in Fig. 12, during which the valve actuating cranks travel from the 125° point to the 180° point in their circle of rotation, in which operation the valve sleeve continues to close the ports in the cylinder and valve casing while the valve piston moves still farther downward through a lost-motion range, as shown in Fig. 12, the mixture being fired at the limit of the compression stroke of the piston to impel said piston on its working stroke, as will be readily understood. On each working or power stroke the piston moves down-

ward and when it reaches the 160° point in the second revolution of its cycle the valve actuating cranks will have moved to the 260° point in their cycle of motion and will 5 have moved the valve sleeve upward to an advanced point with respect to the valve piston in which position the ports 22 and 23 of the valve sleeve, as shown in Fig. 13, will respectively lie immediately below the port 10 4 and above the center of the port 12, the piston being thus on its exhaust stroke and the valve about in position for the exhaust action. On the continued upward movement 15 of the piston to the end of the second revolution of the crank shaft the valve cranks will have moved from the 260° position to the 360° position, at the end of their working revolution, during which the valve sleeve will be moved slowly upwardly so 20 that the port 22 will register with the port 4 for a determined period for the exhaust of the spent gases, while at the same time the valve piston will move upward at a greater rate of speed until, upon the completion of 25 the exhaust action, the ports in the valve sleeve and valve piston will register with each other and with the ports 4 and 12, thus disposing the valve in position for the admission of a fresh charge to the cylinder, at 30 which time a new cycle of action of the engine begins.

It will be observed from the foregoing description that the actuating cranks of the valve sleeve and piston are arranged at different angles with relation to the valve actuating shaft, so that said valve members will have reciprocating motion both in the same and opposite directions simultaneously, as well as variable rates of movement 40 at different points in their travel, to perform the functions described. Also it will be seen that the valve as a whole will move at a much slower rate of speed than the engine piston, with a consequent reduction of wear 45 and tear and less heating from friction, and that, as the valve mechanism is also cooled from the water jacket, the temperature of the working parts of the valve will be kept at a low point. Owing to this fact, and to 50 the fact that the deflector of the valve piston prevents the exhaust from coming fully into contact with the working surfaces of the

valve sleeve, it will be evident that the amount of carbon deposited upon the valve parts will be reduced to the minimum. Furthermore, as the ports in the valve sleeve and valve piston are large or wide, and adapted for the direct travel of the fuel mixture and exhaust gases, it will be evident that restriction in the flow of the fluids will be prevented, allowing a full charge of fuel to be taken in by the engine at all times while preventing any back pressure or heating of the valve due to a restriction or retardation of flow of the exhaust gases through 65 the valve, the advantages of which will be readily understood and appreciated.

I claim:—

In a valve mechanism for internal combustion engines, the combination with a cylinder and piston, said cylinder having an admission and discharge port, and a crank shaft, of a valve casing provided with an inlet port and an exhaust port, arranged respectively below and above the level of 75 said cylinder port, a valve operating in said casing and comprising a hollow sleeve member open at bottom and top and having at one side a segmental inlet port coöperating with the inlet port of the casing and at its opposite side a segmental combined admission and exhaust port, arranged above the level of said inlet port and coöperating with the admission and exhaust port of the cylinder, and a piston member movable within said 80 sleeve member and comprising a cylindrical body closed at top and open at bottom and provided with a diagonal passage coöperating with segmental ports at different levels in the sides thereof arranged for coöperation 85 with the ports in the sleeve member, said piston member having an arcuate deflector projecting from its outer side at its closed end for diverting the exhaust from the valve sleeve, and means for reciprocating said 90 valve members at different speeds from the crank shaft, and both at a lesser rate of speed than the engine piston.

In testimony whereof I affix my signature in presence of two witnesses.
